COIL BINDING MACHINE

Francis E. Wirtz and John M. Klover, Dayton,
Ohio, assignors to General Motors Corporation,
Detroit, Mich., a corporation of Delaware

Application March 28, 1951, Serial No. 217,904

20 Claims. (Cl. 100—10)

1

This invention relates to a machine for tying the coils of an electromagnetic device.

Various methods are used to form and apply windings to electric machines. In some instances the coils are wound directly upon the part of the electric machine adapted to receive them, and in other instances the coils are initially wound on forms or matrices, collapsible to permit removal of the wound, loop-shaped coil for purposes of placing the pre-formed coil upon the part of the electric machine designed to receive and hold it.

Some electric machines require a multiplicity of loop-shaped coils, and to produce them a collapsible form or matrix, having provisions for winding a plurality of coils from a continuous, single wire, is used. This necessitates binding or tying the convolutions of each coil together in order to prevent their complete disintegration when the winding form or matrix is collapsed to permit removal of the coils.

It is among the objects of the present invention to provide an automatic machine which is adapted to receive a form or a plurality of forms upon which coils have been wound and successively tie the convolutions of each coil wound upon said form or forms so that when said forms are collapsed to remove the coils wound thereon, each coil is separately held together and complete disintegration thereof prevented.

A further object of the present invention is to provide an automatic machine adapted to tie the several coils wound upon a collapsible form in such a manner that the binding or tying medium, a wire in this machine, may easily be removed after the tied coil has been placed and secured in proper position on the part of the electric machine designed to receive it. For purposes of economical commercial production and to facilitate removal after assembly, the binding or tying medium must be readily removable yet sufficiently secure to hold the convolutions of the coils together for handling purposes.

Another object of the present invention is to provide a coil tying machine which will be rendered inactive automatically whenever, during the operation of the machine, the form, holding the coil, is not properly clamped and held together for the tying operation.

Further objects and advantages of the present invention will be apparent from the following description, reference being had to the accompanying drawings wherein a preferred embodiment of the present invention is clearly shown.

In the drawings:

Fig. 1 is an end view of the automatic coil tying machine.

Fig. 11 illustrates the power transmission mechanism for revolving the tying needles.

Fig. 12 illustrates the power transmission mechanism for reciprocating the needle housing.

Fig. 13 illustrates the power transmission 30 mechanism for shifting the coil supporting clamp mechanism in both directions.

Fig. 14 is a detail view of the cam of the needle reciprocating mechanism.

Fig. 15 is a similar view showing the cam of 35 the needle revolving mechanism.

Fig. 16 illustrates the cam of the coil supporting clamp shifting mechanism.

Fig. 17 is a detail, fragmentary view of the coil supporting and clamping device.

40 Fig. 18 is a fragmentary, part sectional view showing the binding wire locating and shearing mechanism.

Figs. 19 to 34 inclusive show in schematic form, 45 the progressive functions of the needles at successive intervals during a cycle of machine operation.

Fig. 35 is a diagrammatic view showing the relative functions of the coil indexing mechanism, the needle reciprocating mechanism, the wire 50 shearing mechanism, the needle revolving mechanism and the wire feeding mechanism during a complete cycle of the machine.

Fig. 36 is a wiring diagram illustrating schematically the electrical control mechanism governing machine operation.

Fig. 37 is a part sectional view showing one collapsible winding form on the arbor of the machine.

The machine of the present invention and as illustrated was particularly designed to receive a plurality of collapsible forms or matrices upon each of which six separate coils are wound in loop form. Inasmuch as all of the coils on the several forms are wound from a single or multiple parallel strand of wire, all coils are tied together while on the forms. Each of the two forms or matrices shown held in the machine in Fig. 2 of the drawings comprises a plurality of interfitting sections which when placed together form six side-by-side spools upon which wire may be wound to provide six loop shaped coils. These spools have a rectangular core portion, the two center ones being the larger in transverse dimensions, the next two adjacent core portions being smaller than the two central ones and the two outer core portions being the smallest. Thus the six rectangularly shaped loop coils wound upon the form are of three different sizes each coil having a predetermined number of convolutions of wire. The six coils all tied together by the single wire or parallel wires from which they are wound, are assembled in the stator of the electric motor which in this instance forms the power device of a sealed-in unit of a refrigerator system.

As has previously been stated, in order to avoid complete disintegration of the coils when the collapsible form, on which they are wound, is disassembled for coil removal purposes, it is necessary separately to place a binding cord or wire about the convolution of each, separate coil portion. The tie or bind must be made in such a manner that each must be readily removable when the coil has been assembled into the motor stator. Removal of all ties is especially necessary in sealed-in units for refrigeration systems as foreign matter, which might be loosened and circulate in the closed circuit, is extremely undesirable if not a hazard tending toward complete stoppage of the refrigerant circulatory system.

GENERAL DESCRIPTION OF MACHINE FUNCTIONS

(1) Clamping and indexing

This machine as aforeslated, is adapted to receive two collapsible winding forms and bind or tie each of the respective coils on said forms. A stationary arbor receives the two hollow winding forms which are slidable on the arbor so that the various coils on the forms may successively be moved into the binding position and when all of the coils have been bound may be returned on the arbor to their original starting position. The forms, being collapsible to permit removal of the convolutions of the respective coils, must be securely held together while in the machine to prevent disintegration or flying apart of the windings thereon. For this purpose clamping mechanism is provided, consisting of a rigid clamp jaw and a hinged clamp jaw, each jaw being supported on a block, both of which are secured together in spaced relation and slidable on the machine longitudinally of the arbor. The rigid jaw is engaged by one coil carrying form on the arbor and the second form adjacent thereto is engaged and securely held against its adjacent form by the hinged jaw which is manually operable into its prostrate position to permit placing of the forms upon the arbor and is moved into its erect position as shown in Fig. 2, to engage and hold the forms clamped together on the

arbor. A control switch normally open and connected in circuit with the motor which drives the machine, is closed by the clamp actuating lever when said lever is manually operated to move the hinged clamp into its form engaging and clamping position. As long as the clamp jaws securely hold the coil-carrying forms clamped therebetween the control switch is maintained in circuit-closing position during cycling of the machine. However, if, for some reason, the hinged jaw releases its clamping effort upon the forms on the arbor, permitting the forms to separate, then the control switch is automatically actuated to open the driving motor circuit and stop the machine. Suitable mechanism, later to be described detailedly, moves or indexes the clamping mechanism intermittently in one direction to locate each coil in the binding position and when all of the coils are bound returns the clamping mechanism into its normal, initial position relatively to the arbor.

(2) Binding wire feed, holding and cut-off

The wire supply for binding the coils is led from a supply spool over a pulley supported by the machine. An intermittently actuated one-way clutch operates one of two engaging feed rolls between which the binding wire passes and which draw the wire from the supply spool, through suitable straightening rolls and push it through a suitable conveyor tube to and through suitable shearing and holding blocks located on the machine at the binding location thereon. Driving means for the feed roll clutch is provided for feeding the wire intermittently to the shearing and holding block at properly timed intervals.

A shearing knife cooperatively carried by the shearing block is connected with driving mechanism which intermittently operates said shearing knife to sever a predetermined length of the binding wire from the source of supply at properly timed and recurrent intervals whereby a proper length of binding wire is made available to be drawn against and twisted about each separate coil when it is indexed or moved into the binding position on the machine.

COIL BINDING MECHANISM OF THE MACHINE

The severed length of binding wire held in the holding blocks at the binding location on the machine is grasped, drawn against and twisted about the convolutions at one side of the coil which is being held in the binding location on the machine. The mechanism for grasping, drawing and twisting the binding wire comprises two crochet type needles held in parallel spaced relation directly above the binding location on the machine and being reciprocative toward and away from the binding wire held at the binding location and also being revolvable about the axis of the element supporting said needles. Suitable mechanism for actuating the needles is provided, one mechanism moving the needles downwardly toward the severed piece of binding wire in order to bring the needles into grasping relation with said piece of binding wire and being movable in the opposite direction to draw the binding wire from the holding blocks around the convolutions at one side of the coil. The other actuating mechanism for the needles revolves the said needles about the axis of their supporting and driving shaft so that the grasped wire, drawn about the coil, will be twisted around the coil securely to hold it against disintegration when the coil is

finally removed from the collapsible winding form. The final upward reciprocation of the needles sheds the binding wire about the coil from said needles and thus permits a subsequent indexing which moves the next adjacent coil into the binding position.

The aforescribed functions are repeated during one complete cycle of the machine to bind twelve coils, six of which are wound upon each one of two adjacently clamped winding forms in the machine, each set of six coils having two coils of the same transverse dimensions and largest of them all, two equally sized coils smaller than the previously mentioned two and two coils smaller than either of the two just mentioned. All of the coils on the two spools, as previously mentioned, consist of a plurality of separate convolutions all tied together by the single or plurality strand of wire from which all coils are wound.

THE BODY OF THE MACHINE

As shown in Figs. 1 and 2, the machine consists of a framework rectangular in shape, said framework 20 having an inside partition 21 forming a lower compartment 22 and an upper compartment 23, the top of the frame 24 providing a platform up on which certain elements of the machine are mounted.

POWER TRANSMISSION MECHANISM OF THE MACHINE

In the lower compartment 22, as shown in Fig. 2, there is provided an air reservoir 25 fed from any suitable source of air pressure and connected by any suitable means, not shown, with a clamp returning device to be described later detailedly. The main driving motor 26 of the machine is also located within the lower compartment 22, said motor 26 being connectible with any source of power and having a driving pulley 27 for receiving a belt 28 which is in operative engagement with a pulley 29 supported on the shaft 30, journaled in and extending across the upper compartment 23 in any suitable manner. A standard 31 provides a journal box which rotatably supports the shaft 30 and is secured within the upper compartment 23 in any desirable manner.

The shaft has a hand-wheel 32 secured thereto exteriorly of the machine frame or housing 20. This hand-wheel 32 provides means by which the machine may be manually operated for any desirable reason, such as completing adjustments or moving parts of the machine into any desirable position for checking or adjustment purposes. On the end of shaft 30 opposite to which the hand-wheel 32 is secured there is attached a pinion 35 of predetermined size which meshes with and drives a gear 36. As shown in Fig. 10, this gear 36, of a size so as to be driven at a predetermined speed by the pinion 35, is attached to a shaft 37 rotatably supported in the journal box of a standard 38 also rigidly mounted within the compartment 23. This shaft 37 has a gear 39 secured at the end opposite gear 36, gear 39 in turn meshing with gear 40 which is identical in size to the gear 39. Gear 40 is secured at one end of shaft 41 rotatably supported in the journal box of standard 42 rigidly mounted within compartment 23 of the machine, the other end of shaft 41 having cam 43 secured thereto and a pinion 44. This pinion 44 meshes with a gear 45 mounted upon shaft 46 which is rotatably supported by standard 47 within compartment 23. The relative sizes of the pinion 44 and its meshing gear 45 are such that gear 45 will make one

revolution for each six revolutions of the pinion 44. Shaft 46 upon which gear 45 is mounted also supports cam 50 secured to gear 45 so as to rotate therewith. Shaft 46 also supports a pinion 51 driven by the shaft to drive the gear 52 meshing therewith and mounted upon the shaft 53 journaled in the standard 54 secured within the compartment 23. The relative sizes of the pinion 51 and its connected gear 52 are such the gear 52 will be rotated one revolution for each two revolutions of its driving pinion 51. A cam 55 is operatively secured to the gear 52 so as to rotate therewith. From the aforesgoing description of the driving mechanisms in compartment 23 it may be seen that suitable gearing initially driven by the electric motor 26 operates cams 43, 50 and 55 at predetermined speeds relatively to one another. The cam 43 may be termed the "needle revolving cam" inasmuch as it acts through its operative connections with the needles to revolve said needles in either direction for purposes and in a manner to be described. The cam 50, which may be termed the "needle reciprocating cam," acts through its connections with the needles and particularly the needle supporting housing, to reciprocate said needles toward and away from the coil to be bound as will be detailedly described. The cam 55 which may be termed the "coil-form indexing cam," operates through its connections with the coil clamping mechanism intermittently to move the clamped forms along the arbor of the machine in one direction of the cam, having provisions when all of the coils have been completely bound to render the form returning air cylinder effective to move the coil supporting forms back to their original positions upon the arbor.

The platform 24 supports various parts of the machine which cooperate to perform the coil tying or binding operation.

FORM CARRYING AND CLAMPING MECHANISM

Figs. 2, 4, 5 and 5A clearly illustrate the mechanism which supports the coil bearing and clamping mechanism. Upon the platform 24 there is secured a rigid standard 60 which supports an arbor 61 so that said arbor extends longitudinally above the platform 24 and substantially parallel thereto. This arbor receives the collapsible coil carrying forms 62 and 63 which are slid upon the arbor 61 by the operator. The Figs. 7 and 37 illustrate the collapsible form shown in dot and dash lines in Fig. 2. Each form consists of two oppositely disposed body portions 62a and 62b presenting six side by side spool areas, the two inside ones being the largest transversely, the next two being smaller and the final, outer two being the smallest in transverse dimensions. When applied to the arbor 61 of this machine, each form has a winding on each spool area, the six windings on a form being of a single, continuous wire 62c and thus tied together as shown in Fig. 37. The arbor 61, as shown in Fig. 7, spreads the form bodies to hold the windings thereon substantially taut and intact. When removed from arbor 61, the form bodies are easily removable from the wire convolutions. In order to prevent disintegration or flying apart of the windings on the form, said forms must be placed over the arbor. The forms are clamped together tightly to assure proper location and indexing. For this purpose clamping mechanism has been provided on the machine. Two spaced and parallel rods 64 and 65 are secured to the platform

24 so as to be slightly above said platform, said rods forming slide bars for the clamping mechanism. The clamping mechanism consists of two clamping jaws 66 and 67 the former being erect and rigid, the latter being movable from a prostrate position substantially parallel to the platform 24 into the erect position, as shown in Fig. 4, in which said clamping jaw is substantially at right angles relative to said platform. Each jaw is carried by a block, the jaw 66 by block 68 which is slidably mounted upon the slide bars 64 and 65 and rigidly carries the jaw 66 so that it constantly is in its erect position as shown in Fig. 4, the jaw 67 being hingedly carried by the block 69 also slidably carried upon slide bars 64 and 65, jaw 67 being movable between its prostrate and erect positions relative to its support block 69. Both supporting blocks are secured together in spaced relation in any suitable manner so that both may move in unison along the slide bars 64 and 65 and remain in proper spaced relation. When the coil supporting forms 62 and 63 are placed upon the arbor 61 by the operator the coil supporting form 62 is moved to abut against the rigid clamping jaw 66 while the hinged clamping jaw 67 is in prostrate position. After the coil supporting form 62 engages the clamp 66 the hinged clamp 67 is actuated from its prostrate position to its erect position as shown in Figs. 2 and 4, at which time said clamping jaw 67 engages form 63 and securely clamps it against its associate form 62 on the arbor 61.

A rod 70 is rotatably carried by the block 69, said rod having the jaw 67 attached thereto so that said jaw may be rotated relatively to its supporting block 69. Rod 70 also has a lever 71 attached to it, this lever being connected to the rod 73 by any suitable means which causes the lever 71 and rod 70 to be moved positively counterclockwise by the pushing effort of rod 73 toward the left as regards Fig. 2 and which applies a constant, yieldable pressure against lever 71 in a clockwise direction as the rod 73 exerts a pulling effort upon lever 71 toward the right whereby rod 70 is rotated to move jaw 67 into its erect, form-engaging position. In this machine, the yieldable connection between lever 71 and rod 73 consists of a slidable saddle on rod 73 and engageable on one side with a shoulder on the rod 73. The other side of the slidable saddle abuts against a spring 72 about the rod 73 and held thereon by lock nuts on said rod. Rod 73 has its opposite end pivotally secured to a lever 74 at a predetermined point 77 between the free end of said lever 74 and the end thereof attached to the rod 75. Rod 75 is supported on the block 68 carrying the rigid clamp jaw 66. At the end of rod 75 opposite the lever 74 there is attached a crank 76 which is manually operable to rotate the rod 75. When the crank 76 is rotated counterclockwise as regards Figs. 4, 5 and 5A, the rod 73, secured to the lever 74, moves toward the left and thus the shoulder on rod 73, engaging the saddle to which lever 71 is attached, positively actuates the hinged clamping jaw 67 from its erect to its prostrate position in which it lies substantially parallel to the platform 24. This operation is necessary to permit removal from and placing the coil supporting forms upon the arbor 61. After the coil supporting forms 62 and 63 are placed on the arbor and moved to engage the rigid clamping jaw 66, the clamp 76, operated clockwise by crank 76 and its rod connection 73, moves the hingedly 75

clamped jaw from its prostrate to its erect position as shown in Figs. 2 and 4.

The relative positions of the rod 73 and lever 74 to which it is pivotally connected, at the time jaw 67 engages the coil carrying form 63 are shown in Fig. 5A by the dot and dash lines. At this time spring 72 is not compressed. In order to compress said spring so that it exerts a constant clockwise turning effort upon lever 71 to maintain the jaw 10 76 in proper clamping engagement with the form 15 63, the lever 74 is moved beyond its dot and dash line position and into its full line position as shown in the Fig. 5A. In this position the center line of rod 73 and therefore its pivotal point of 20 connection 71 with lever 74 lies beneath the axis of the rod 75, supporting lever 74, thereby providing an over-center, toggle connection which locks the lever 74 in this position under the tension of spring 72 until manual operation of crank 25 76 counterclockwise again moves lever 74 toward the dot and dash line position as indicated in Fig. 5A.

A safety switch, in circuit with the main driving motor of the machine, is controlled by the 25 afore-described clamp-operating mechanism. So that as long as the clamp-operating mechanism under the effect of spring 72 functions securely to hold the coil-supporting forms in properly 30 clamped position between the jaws 66 and 67, said switch will maintain machine operation. However, if for any reason the clamping effort upon the coil-supporting forms 62 and 63 is relaxed or released and thereby permits loosening 35 of the coils on the forms, this switch is automatically actuated to break the motor circuit and stop the machine. Fig. 8 together with Figs. 2, 4 and 5 illustrate this safety mechanism. The switch 80 is mounted upon the platform 24, said switch normally closing the electric circuit in 40 which it is connected. Upon the platform 24 there is mounted a bracket 81 which has a rod 82 hingedly supporting a block 83. This block provides a track 84 which is substantially parallel with the clamp-supporting slide bars 64 and 65. Rod 82 also carries an arm 85 angularly shaped 45 to extend over and above the actuating button or member of the switch 80. A spring 86, interposed between the platform 24 and the end of the angular arm 85, normally yieldably urges the arm 85 to rotate rod 82 and its attached block 83 so that arm 85 engages the operating member of the 50 switch 80 to hold it in circuit breaking position. The lever 74 of the clamp-actuating mechanism carries a roller 87 which, when the clamping 55 mechanism is moved into form-clamping position, engages the track 84 as shown in Fig. 5A, moving said track and its block 83 to raise the arm 85 away from said switch 80 against the effect of spring 86 whereby said switch 80 is permitted to 60 close its circuit. The roller 87 on the lever 74 of the clamp-actuating mechanism rides on the track 84 as the clamping mechanism is moved along the slide bars 64 and 65 intermittently to bring the respective windings or coils on the forms 65 62 and 63 into the tying position on the machine. Thus, if the clamping mechanism tightly holds the forms 62 and 63 clamped between the jaws 66 and 67 during the entire cycling of the machine, the arm 85 is maintained out of engagement with the switch 80 and permits it to remain closed. However, if for any reason the hinged clamping 70 jaw 67 is moved to relax its clamping effort upon the forms, lever 74 will be moved to disengage its roller 87 from the track 84 permitting the spring 86 to move the arm 85, block 83 and its attached

track 84 in a manner to cause arm 85 to engage switch 80 and actuate it to break its circuit and thus stop the machine.

BINDING WIRE SUPPLY AND FEED MECHANISM

Figs. 2, 4, 5 and 8 show the binding wire supply and feeding mechanism mounted upon the platform 24. The binding wire supply is directed over roll 90 and carried upon a standard 89 secured to the platform 24 adjacent the rigid standard 60. From the roll 90 the binding wire 91 extends through a guide block 92 secured to a block 93 which carries three straightening rollers 94, 95 and 96 in staggered relation and between which the wire passes in order to remove bends or kinks therein. Another block 97 mounted upon the standard 89 adjacent the block 93 carries three wire straightening rollers 98, 99 and 100 the axes of which are angularly displaced relatively to the axes of the straightening rollers 94, 95 and 96. Two frictionally engaging rollers 101 and 102 have the binding wire 91 extending therebetween, these rollers providing the motivating means for feeding the wire to the binding location on the machine. Roller 101 is attached to a shaft 103 (see Fig. 8), which is secured to one portion of a one-way clutch 104, of any suitable design. The other portion of the one-way clutch has an arm 105 extending therefrom by means of which said clutch portion is oscillated in one direction and the other for actuating the feeding roll supporting shaft 103. This clutch 104 is of the standard type so that when the portion thereof with extending arm 105 is moved counterclockwise its cooperating portion will actuate the attached shaft 103 in a counterclockwise direction so that the feed roll 101 is operated in the same counterclockwise direction as regards Fig. 4. However, when the extending arm 105 on the one clutch portion is actuated in the opposite or clockwise direction the clutch mechanism is released and the portion of which the arm 105 forms a part can rotate clockwise relatively to the portion to which the shaft 103 is secured. Thus, as the arm 105 is moved counterclockwise the feed roll 101 with the binding wire clamped between it and its associated roll 102 moves the binding wire forwardly or toward the left as regards Fig. 4, a distance in accordance with the range of movement of the arm 105 counterclockwise. Reverse movement of said arm 105 clockwise moves only one portion of the clutch backward, the other portion of the clutch, operatively connected to the feed roller 101, remaining immovable. In order to assure immovability of the clutch portion secured to the feed roll 101, as the clutch portion having lever arm 105 moves clockwise, the clutch portion attached to feed roll 101 has a drum 106 (see Fig. 8) frictionally engaged by a brake band 107, one end of which is attached to the shorter end of a lever 108 pivoted on the standard 89 at 109, the other end of said brake band 107 being secured to the longer end of lever 108. A spring 110 is anchored between the lever 108 and the platform 24 urging the lever 108 clockwise about its pivotal support 109 and thereby exerting a braking effort upon the one clutch portion attached to the shaft 103 of the feed roll 101 when the portion having arm 105 is rotated clockwise, as regards Fig. 4 and practically no braking effort upon said one clutch portion when the clutch portion having the arm 105 is moving counterclockwise to actuate the feed roll 101 for drawing binding wire from the roll 90 and feeding it toward the tying position on the

machine. The arm 105 of the one clutch portion has a link 112 connected thereto which extends through an opening in the platform 24, into the compartment 23 of the machine and is actuated by mechanism to be described detailedly hereinafter.

As the feed rolls 100 and 102 move the binding wire intermittently from the spool 90 toward the binding location on the machine they push the wire through a suitable conduit 120 attached at one end to the standard 60, extending through a channel in the arbor 61 and terminating at the shearing block 121 which is secured in the longitudinal channel in the arbor 61, said arbor being attached to the standard 60 and extending therefrom. The shearing block 121 has a tapered opening 123 through which the binding wire 91 extends to pass through the spaced, apertured supporting blocks 124 and 125 secured in the arbor channel and forming the binding location on the machine. A rod 126 rotatably supported in shearing block 121 has a shearing knife 127 secured thereto so that said shearing knife 127 cooperates with the block 121 to sever the binding wire at the end of the block 121 adjacent the supporting block 124 thereby providing a predetermined length of severed binding wire 91 which, as shown in Fig. 18, is supported at the binding location on the machine by the blocks 124 and 125. This rod 126 extends longitudinally of the arbor 61 to an aperture in the supporting standard 60 where a lever 130 is secured to said rod 126. This lever 130 has its free end connected to a link 131 shown in Figs. 2 and 4, said link extending through an opening in the platform 24 into the compartment 23 where it is operatively connected to the mechanism for actuating the shearing knife which mechanism will later be described detailedly. A spring 132 is provided on the knife-actuating rod 126, said spring yieldably maintaining the rotatable shearing knife 127 in operative engagement with the shearing block 121.

CARRIER AND DRIVES FOR BINDING NEEDLES

Figs. 4 and 7 illustrate the needle supporting and actuating mechanism and will be referred to for this description. As shown in these figures, the platform 24 has two spaced standards 140 and 141 provided with rigid slide bar extensions 142 and 143 vertical relative to the platform 24. The standards 140 and 141 are arranged at one side of the arbor 61 and secured upon the platform 24 so that the binding stage on the machine is directly central of said standards. Slide bars 142 and 143 slidably carry a housing 144 which contains the needle driving mechanism as shown in Fig. 7. Intermediate the portions 144a and 144b of housing 144 which slidably embrace the respective slide bars 142 and 143, there is provided a central lug 145 to which one end of a lever or link 146 is hingedly connected. The other end of this link extends through an opening in the platform 24, and is connected to the mechanism which not only supports the housing 144 upon slide bars or rods 142 and 143 but also is operative to move the housing 144 upwardly or downwardly through its reciprocating cycles. This needle reciprocating mechanism will be described detailedly hereinafter. Fig. 7 shows the link 146 provided with adjusting mechanism 147 whereby the region of travel of the housing 144, while reciprocated, may be adjusted.

Between the two portions 144a and 144b of the housing 144, slidably engaging the slide bars 142

and 143 there is provided a tubular portion 148 in which bearings for the drive shaft 149 are provided in any suitable manner. The one end of this drive shaft 149, as shown in Fig. 9, extends through an opening in the platform 24 into the compartment 23 and is operatively connected with mechanism which not only permits longitudinal reciprocation of the rod 149 as the housing 148 is reciprocated along the slide bars 142 and 143, but also is operative to rotate said drive rod 149 back and forth for revolving the needles as will be described. The opposite end of the drive shaft 149 has a pinion 150 attached thereto which meshes with an idler gear 151 supported on stub shaft 152, journaled in the housing 144. The idler gear 151 meshes with another pinion 153 secured to shaft 154 which is journaled in the central tubular portion 155 of the housing 144. Shaft 149 may therefore be termed the "needle driving shaft" while shaft 154 may be termed the "needle supporting shaft" for, at the end of shaft 154, extending outside the housing portion 155, a fixture 156 is provided by means of which two crochet type needles 157 are secured to shaft 154. This fixture 156 provided on shaft 154 secures the shank ends of needles 157 to shaft 154 so they extend longitudinally therefrom parallel to each other and equally spaced, on each side of the axis of shaft 154, as shown in Fig. 4. The free end of these needles extending downwardly from the housing 144 toward the binding location on the machine are of the crochet needle type having hooked ends 158, said hooked ends being oppositely disposed, that is, when in normal position, as shown in Fig. 7, the open hook end of one needle faces toward the housing actuating link 146, while the other needle has its open hooked end facing in the directly opposite direction. Fig. 7 shows that these needles 157 are aligned with the binding wire supporting block 125 and as viewed in Fig. 18, both needles are substantially parallel and spaced so that when lowered they will enter between the supporting blocks 124 and 125 carried in the channelled portion of the arbor 61. From this it may be seen that as the housing 144 is reciprocated on its guide bars 142 and 143, the needles 157 and particularly their hook ends 158 are moved toward and away from the supporting blocks 124 and 125 between which the binding wire is supported. Also when the drive shaft 149 is rotated in one direction or the other, the connected gears 150, 151 and 153 will rotate the shaft 154 in one direction or the other respectively thereby revolving the needles 158 about the axis of the shaft 154 in the direction in which said shaft is rotated. Normally, that is, when the machine is in its inactive position ready to start a cycle, needles 157 are above the supported binding wire 91 and in alignment therewith, one open end of the needle facing one side of the wire while the open end of the other needle faces the opposite side of the supported binding wire. If lowered completely, without being revolved, the needles would strike the severed piece of binding wire in blocks 124 and 125. (See Fig. 19.)

From the foregoing description it will be evident that certain parts of the machine are initially operated manually and do not depend upon the power actuated portions of the machine to perform their functions. This operation, independent of the power driven portions of the machine, consists of the placing of the two coil supporting, collapsible forms upon the arbor and the manual actuation of the clamping mechanism by crank 76 securely to clamp said forms together.

while slidable on the arbor, said clamping mechanism, when actuated to hold the coil-supporting forms together, also rendering a safety switch effective to maintain the electric circuit to the power actuating motor as long as the forms are securely clamped together.

After the forms are clamped together upon the arbor the machine is started and its functions for tying the twelve separate coils on the two forms in proper succession is initiated.

FUNCTIONS OF THE MACHINE TO TIE A SINGLE WINDING

Nine functions or steps of operation are necessary to tie a single coil, these nine steps being successively repeated twelve times in order to tie all of the twelve separate windings on the two forms held in the machine.

Step 1.—The wire feeding rolls 101 and 102 are rendered operative to convey wire from the supply spool over pulley 90 through the straightening devices and the conveying conduit to the cut-off or shearing block 121 and through the aligned aperture in the spaced supporting blocks 124 and 125. The actuation of these feed rolls 101 and 102 in this cycle of operation is such that a predetermined length of wire 91 extends beyond the final supporting block 125, as shown in Fig. 18. The shearing knife 121 then is rendered operative to sever the predetermined length of wire 91 as supported by blocks 124 and 125. It will be understood that the blocks 124 and 125, being supported in a grooved portion of arbor 120, position said severed length of binding wire 91 transversely of the coil being held in the binding position and substantially through the center of its loop opening, as shown in the diagram, Fig. 20.

Step 2.—(See Figs. 21 and 22.) After the wire is in position the needle-carrying housing 144 is reciprocated downwardly along its supporting slide bars or rods 142 or 143 thereby causing the needles to descend toward the coil to be bound, which has originally been properly positioned relatively to the needles by the placement of the winding supporting forms on the arbor and between the two clamping jaws 66 and 67. The position of the needles as shown in Fig. 22 is such that they respectively pass equidistantly alongside the convolutions at the top-side of the coil held in the binding location. This initial descent of the needles downwardly is continued until the needle hooked ends are beneath the coil convolution therebetween and yet above the severed length of the binding wire held between blocks 124 and 125. Then Step 3 is initiated.

Step 3.—(See Figs. 23 and 24.) The needle driving shaft 149 is rendered effective to act through gears 150, 151 and 153 to rotate the needle-supporting shaft 154 in one direction (here referred to as "backward") whereby the needles 157 are revolved backward 30° which disalign them with the severed piece of binding wire supported by blocks 124 and 125 but still maintaining said needles out of contact with the coil convolutions therebetween.

Step 4.—(See Figs. 25 and 26.) Following the function (3), the needle housing reciprocating mechanism is again rendered active to move the housing 144 downwardly on its supporting rods 142 and 143 in order to bring the hooked ends of the needles below the binding wire 91 in blocks 124 and 125.

Step 5.—(See Figs. 27 and 28.) Now the needle revolving mechanism is again rendered active to revolve the needles in the opposite or forward di-

rection substantially 35° which places the hooked ends of the effective needles directly beneath the severed piece of binding wire.

Step 6.—(See Figs. 29 and 30.) Now the needle housing reciprocating mechanism becomes active to move the housing and its supported needles upwardly on rods 142 and 143 thereby raising the needles or moving their hooked ends away from the wire supporting blocks 124 and 125. As the needles move upwardly their hooked ends will grasp the wire 91 between the blocks 124 and 125 drawing the severed piece of binding wire from the supporting blocks as indicated in the diagrammatic views, Figs. 29 and 30. During this movement of the needles the binding wire 91 is drawn upwardly around the convolutions of the located coil and at the completion of this upward movement of the needles the wire is placed in a position relatively to the coil as indicated in Figs. 31 and 32.

Step 7.—The needle revolving mechanism becomes effective after completion of the Step 6 to revolve the needle substantially 355° in a forward direction which twists the wire about the coil convolutions as shown in Figs. 33 and 34.

Step 8.—After the twisting operation has been completed the needle-reciprocating mechanism again becomes effective to raise the needles into their initial or normal positions resulting in a shedding of the twisted tie wire surrounding the located coil. (See Fig. 34.)

Step 9.—The needles are then revolved backward substantially 360° in order to locate them and their driving mechanism in proper position preparatory to the next following operation on the next adjacent coil to be moved by the indexing mechanism.

In order to locate the next adjacent coil in the proper binding position on the machine the indexing mechanism for shifting the form supporting and clamping mechanism longitudinally of the arbor again becomes effective whereby the second coil on spool #1 is moved into alignment with the needles so that upon their next descent the needles will pass alongside the second coil as indicated in Fig. 22. It will be understood that these nine aforescribed steps of operation together with the indexing operation are repeated for each one of the twelve respective windings supported upon the two forms 62 and 63.

It will also be noted that each one of these forms carries three different sized coil windings, that is, the two innermost and adjacent windings on each form are the largest, the two outer or extreme windings are the smallest and the two intermediate windings are of an intermediate size. Thus, it is necessary in order to compensate for these different size coils on each form to have the needles move to a different position in Step 6 for each pair of differently sized windings on a form. More specifically, for the two smallest or outer windings on the one form, the needles in Step 6 must move upwardly a predetermined distance in order to clear the coil and complete the twist about the convolutions of these windings, for the two intermediate coils the needles must move upwardly a greater distance to clear and complete the twisting operation about these larger windings and for the two adjacent inside and largest windings the needles must move upwardly a still greater distance in order to complete its twisting operations for these particular windings. Therefore, the reciprocating mechanism which controls the upward and downward movement of the needle supporting housing 144

is designed to move the housing upwardly into the necessary positions for binding these respective and differently sized windings.

SEQUENCES OF MACHINE OPERATIONS AND DRIVING MECHANISMS FOR EFFECTING THESE FUNCTIONS

Assuming that the first coil on the first coil-bearing form 62 has been completed and the machine has returned the needle-supporting housing to its initial normal position, the clamping mechanism which securely holds the winding-supporting forms clamped together on the arbor 61 will be actuated to index or move the second coil on form 62 into the binding position. The mechanism for so actuating the form clamping mechanism is illustrated in Figs. 3, 13 and 16. The block 69 supporting the hinged clamp 67 is operatively connected to the block 68 supporting the rigid clamp 66 so that both blocks move together in spaced relation along their support slide bars 64 and 65. As shown in Fig. 4 the block 69 has a depending ear 170 which extends through an elongated opening in the platform 24 into the compartment 23 of the machine. One end of the longitudinally adjustable link 171 is hingedly secured to the said ear 170, the other end of this link being hingedly secured to one end of lever 172, the opposite end of this lever being pivotally secured to a bracket 174 attached to the partition 21 in the frame of the machine. Between the two ends of lever 172 a cam follower roller 175 is rotatably secured to said lever, this cam follower 175 being adapted to ride upon the outer contour or cam surface of the indexing cam 55 which is carried and driven by the gear 52 supported on shaft 53 journaled in the standard 54 which is mounted upon the partition 21 of the machine frame. The Fig. 16 illustrates this indexing cam clearly showing its outer camming conformation which is engaged by the cam follower 175 and actuates the lever 172, link 171 and the ear or lug 176 on the frame clamp to move the clamp forward intermittently at predetermined intervals and for predetermined lengths so as to bring the respective windings on the two forms 62 and 63 successively into the proper alignment with the needles 157. The first coil or winding on the frame 62 is wound while the follower is in the position as shown in Fig. 13. As the cam rotates clockwise as regards Figs. 13 and 16 the follower will ride over the 20° dwell as shown in Fig. 16 during which time the winding supporting spools are held by clamping mechanism in the binding position. At the time the first coil is completely bound the follower 175 will have reached the beginning of the 10° lead or rise designated by the numeral 176 thereby causing the lever 172 to be moved clockwise about its pivotal spool on bracket 174 and consequently causing the link 171 through the lug connection 170 to move the clamping mechanism with its spools therebetween toward the right as regards Fig. 2 and thus bring the second coil on spool 62 into the binding position or more particularly into operative relation with the needles 157. While the second coil is being bound the follower rides upon the second dwell of 22° . When the second coil is completed the follower will meet the 8° lead 177, Fig. 16, this cam lead again actuating the lever 172 and link 171 to the right as regards Fig. 3 whereby the frame supporting clamping mechanism will again be moved in order to bring the coil #3 on spool 62 into proper binding position. As shown in Fig. 16, this shifting of the

spool-clamping mechanism toward the right will be repeated intermittently and at proper intervals until the last coil or winding on spool 63 is in the winding position at which time the cam follower 175 will ride along the 22° dwell indicated by the numeral 178 in Fig. 16. When the said last winding on spool 63 is completed, the cam 16 will have rotated clockwise so as to bring the receding surface 179 into alignment with the cam follower 175 at which time said follower will move from the high level 178 in Fig. 16 to the initial low level in which it is shown in Fig. 13. This movement of the lever 172 as the follower rides over the dropped surface 179 effects a return of the clamping mechanism from the extreme right position where the coil-supporting frames 62 and 63 are on the arbor adjacent its supporting standard 60 into the initial loading position as shown in Fig. 2.

Figs. 3 and 13 illustrate the mechanism by means of which this lever 172 is moved in this counterclockwise direction about its supporting standard 174. This mechanism consists of an air cylinder 180 of any standard design, the air cylinder containing a piston to which rod 181 is connected. The outer end of the rod is anchored to the lever 172 by the pin 182. The end of the cylinder opposite from which the piston rod extends is hingedly secured to one end of a link 183, pivoted to the standard 54 at the point 184 substantially intermediate the end of lever 183, the opposite end of said lever being hingedly secured to an adjustable link 185 which is also hingedly attached to the standard 54 by the pin 186. The portion of the interior of the cylinder on the rod side of the piston is connected with the air supply reservoir 25 provided in the compartment 22 of the machine. The opposite end of the cylinder 180, or more particularly, the end of the cylinder supported by the hinged lever 183, has an air flow restricting opening by means of which air on the side of the piston opposite the rod 181 may escape restrictively. The air pressure in the cylinder on the rod side of the piston, not shown in the drawing, is constantly urging the piston in the cylinder 180 to move the rod inwardly whereby a pulling force is exerted upon lever 172 in order to maintain the cam follower 175 on lever 172 in engagement with the camming surface of the cam 55. When the follower reaches the receding surface 179 on the cam 55, the cylinder, under the effective air pressure, becomes operative quickly to move the piston in the cylinder toward the left as regards Fig. 3 and consequently the lever 172 is actuated counterclockwise to return the cam follower 175 into the normal position from the highest camming surface 178 to the normal position shown in Fig. 13. In order to prevent the striking of the cam follower 175 against the lowest cam surface with a damaging blow, the air on the side of piston opposite the rod 181 is exhausted through the restricted exit orifice which retards substantially the movement of the piston in the cylinder 180 under the effect of air pressure to return the follower 175 to normal position. Thus the cylinder 180 performs a double function, under the effect of air pressure it maintains the cam follower 175 in constant engagement with its cooperating cam 55, quickly returning the cam follower 175 to normal position at the drop off surface 179 on the cam but controlling said quick return in such a manner that damaging bottoming of the cam follower 175 against the lower dwell surface is prevented.

The gear 52 upon which the cam 55 is mounted is driven by pinion 51 which rotates through two revolutions in order to rotate the cam 55 through one revolution. Gear 51 as shown in Figs. 10 and 13 is supported on shaft 46 which also carries the gear 45 meshing with the pinion 44 on shaft 41. Pinion 44 must rotate through six revolutions in order to rotate its cooperating gear 45 one revolution. Shaft 41 which supports pinion 44 also carries the gear 40 which operatively meshes with a similarly sized gear 39 on shaft 37. This shaft 37 also carries a gear 36 meshing with pinion 35, which, as has been previously described, is carried by shaft 30 provided with the driving pulley 29 operatively connected with the driving motor 28.

The cam 55, as shown in Fig. 13, supports a switch actuating cam block 187, adjustably secured thereon, this cam block being operative to engage a switch actuating lever 188 at a proper time to stop machine operation when the spool-carrying clamping mechanism has been moved to full return or load position.

A pivot rod supported by the standard 54 has two levers 188 and 189 attached thereto. Lever 189 has a spring 190 secured to its free end, said spring urging connected levers 188 and 189 clockwise as regards Figs. 3 and 13 so that lever 189 may engage and actuate switch 191 from its normal open position into its circuit closing position. Spring 190 is effective to maintain switch 191 closed as long as lever 188 is not engaged by the block 187 on cam 55. When said cam 55 has made one complete revolution during which time all windings on forms or spools 62 and 63 have been bound and the forms again returned to initial loading position, lever 188 is engaged by block 187 on cam 55 and actuated to rotate it and its connected lever 189 counterclockwise thereby positively moving lever 189 to disengage the switch 191 and permit its actuating member to return to normal circuit breaking position which will stop machine operation. Thus, the cam 55 actuates mechanism which renders the control switch 191 effective for stopping machine operation when the coils on both forms 62 and 63 have been completely bound and returned to their normal load position on the arbor 61 by the form clamping mechanism, and also renders said switch ineffective during cam rotation to complete coil binding operations.

After the coil to be bound is properly located, it is necessary to introduce the binding wire into the proper position relative to the coil in order to provide the proper length of binding wire. It has been previously described that the binding wire is drawn over the spool 90, passing through straightening devices and then is urged or pushed through a conveyor conduit to and through the shearing block 121 and the supporting blocks 124 and 125. The feed rolls 101 and 102 which move the wire in this feeding direction toward the supporting blocks are actuated by a link 112 which extends through an opening in a platform 24 down in the compartment 23 of the machine and is operatively connected with the gear 36. (See Fig. 12.) This connection, as shown in Fig. 10, may be made by any suitable eccentric device in this instance shown in the form of a block 195 mounted on gear 36 eccentrically thereof, this block having a longitudinal slot for receiving a headed pin 196 to which it attached the saddle 197 having the one end of link 112 connected thereto in any suitable manner. This connection is adapted to be adjusted for varying the eccen-

tricity of the rod 112 relatively to the gear 36 whereby the rotational distance of the feed roll 101 is controlled. This eccentricity may be increased or decreased by adjustment of headed pin 196 in the slotted block 195, said slot being radial of the gear 36. It will, of course, be understood that when the eccentric connection on gear 36 moves the link 112 upwardly the feed roll 101 is actuated through its clutch connection to move the binding wire over the spool 90 toward the support blocks 124 and 125 and on the contrary when the eccentric connection on gear 36 moves link 112 downwardly as regards Figs. 4 and 12, then the feed roll 101 is released by the clutch mechanism to permit the free return of the clutch into its initial position. Thus, the feed roll 101 is operated through its feeding cycle for one-half revolution of the gear 36 and is held immovable by the brake band 197 on said feed roll to permit return of the clutch to initial shifting position during the other half of the rotation of gear 36.

Figs. 3, 10 and 12 show a similar eccentric connection including a block 200 and saddle supporting pin 201 secured to the gear 40 eccentric thereof. The supporting pin 201 has the saddle 202 mounted thereon which is operatively connected with link 131 described heretofore as being the shearing knife actuating link secured to the knife supporting shaft 126. This eccentric connection with gear 40 actuates the link 131 in one direction for one-half revolution of gear 40 to rotate the rod 126 so that the shearing knife 127 thereon severs a predetermined length of binding wire from the feed supply and supported by the blocks 124 and 125. During the other half of the one revolution of gear 40 the eccentric connection with link 131 moves the shaft 126 to return the knife 127 to its normal position preparatory to a repeat shearing operation.

The next functional cycle of the machine performs the actual tying operation and involves the needle operating mechanism including cams 43 and 50. Cam 43 is the one that effects needle revolving movements and cam 50 operates the needle supporting housing to effect reciprocation of the needles toward and away from the windings to be bound. The first operation of the needles to bind a properly located coil or winding is to move downwardly toward said winding, this movement being effected by cam 50 in the following manner:

Referring particularly to Figs. 3, 10, 12 and 14, it will be seen that cam 50 which performs the function of raising and lowering the needles is supported by shaft 46 journaled in the standard 47 which is mounted upon the partition 21 of the machine frame. This cam 50 is carried and driven by the gear 45 which in turn is driven by the pinion 44, said pinion being one-sixth the size of gear 45 so that for every six revolutions of pinion 44, gear 45 and its attached cam 50 make one revolution. For one revolution of cam 50 the six windings on one spool, for instance, spool 62 are tied with binding wire, the cam 50 on its second revolution effecting the binding of the winding upon the frame 63. A hanger 221 is secured to the bottom, inside surface of the platform 24, said hanger having one end of a lever 222 hingedly attached thereto, the other end of said lever being forked and attached to the link 146 which, as previously described, is secured to the needle carrying housing 144. (See Fig. 7. Between the ends of the lever 222 there is provided a cam follower roll 223 which is urged and maintained in riding engagement with the

peripheral camming surface of cam 50 by a spring 224, one end of which is attached to the lever 222, the other end to the standard 47. Fig. 12 shows the relative position of the cam follower 223 to the cam 50 at the start of a machine cycle. It will be noted that the roller is riding upon the dwell surface 226 of cam 50 at a point thereon from which the follower 223, upon rotation of cam 50 counterclockwise, rides upon the descending surface 227 of the cam thereby permitting the spring 224 to become effective to move lever 222 counterclockwise about its pivotal support on hanger 221 and consequently move the link 146 downwardly as regards Figs. 3, 7 and 12. This down movement of the link 146 will move or reciprocate the housing 144 downwardly on its pedestal or slide rods 142 and 143 so that the needles 151 are moved toward the winding maintained by the clamp in the binding position on the machine which, as has been mentioned, is in alignment with the descending needles 151. In descending the cam surface 227 roller 223 will finally reach its extreme bottom end following which continued counterclockwise rotation of cam 50 will cause the roller to move over the rise surface 228 of the cam. Thus, as the needles move downwardly from the start position shown in Figs. 19 and 20 they finally reach the position shown in Figs. 25 and 26 where their hooked ends are beneath the level of the binding wire supported between blocks 124 and 125 from whence, in response to the raising of link 146 by the cam follower 223 riding the rising surface 228 on the cam, the needles are moved upwardly to grasp the binding wire and draw it from the supporting blocks upwardly toward the one side of the coil winding to be wound as indicated diagrammatically by Figs. 29 to 32 inclusive. From the rising surface 228 of the cam the roller reaches and rides upon the dwell surface 229 thereby actuating the lever 222 to move the link 146 into position in which the hooked ends of the needles are in a predetermined position above the level of the coil to be bound. As has previously been said, windings on the frame and, for instance, the frame 62 which is the first winding supporting frame in position, are of three different sizes, the first winding to be bound thereon being the smallest, the second a little larger in transverse dimensions, the third the largest in transverse dimensions, the fourth being the same as the third, the fifth the same as the second and the sixth the same as the first, the same being true of the winding on the form 63. Thus, when the follower 223 reaches and travels over the dwell surface 229 of the cam 50 the wire grasping hook ends of the needles are brought above the level of the top side of the smallest or No. 1 coil on frame 62 as indicated diagrammatically by Fig. 32. It is during this time that the needles are revolved and twist the wire as shown in Fig. 34. When the twisting operation is completed the needles are again moved upwardly to shed or separate the needles from the wire now twisted and to return the needles to their normal, up position. This is accomplished by the cam follower 223 riding the rising surface 230 of the cam, the follower, when reaching the dwell surface 231, having actuated lever 222 so that through its link 146 the needle housing is again returned to its normal up or start position. During the riding of the roller 223 over the dwell surface 231 the needles are revolved 360° to return them to their normal position as the cam follower 223 again descends the declining surface 232 of the cam. This aforescribed

needle operation is again repeated for the coil No. 2 on form 62 which in the meantime has been moved into operating alignment with the needles.

It will be remembered that coil No. 2 is of greater transverse dimensions than coil No. 1 and therefore said needles must be moved to a higher position to clear this coil for the twisting operation. Thus, when the cam follower 223 reaches the dwell surface 233 on cam 50 the needles will be in a position directly above the larger diameter winding No. 2 on form 62 for the radial distance of the dwell surface 233 from the center of the cam is predeterminedly greater than the radial distance of the dwell 229, from the cam center. The operation on coil No. 3 is started when the cam follower descends the declining surface 234 of the cam 50. Coil winding No. 3 being the largest in transverse dimensions the needles must be raised still higher than for windings 1 and 2 to permit the binding wire twisting operation and therefore dwell 235 on cam 50, which is traversed by the cam follower during the twisting operation of the binding wire around winding or coil No. 3, is farther from the center of the cam than either of the other two corresponding dwells 229 or 233. Binding of coil No. 4 is initiated as the follower descends the declining surface 236 of the cam, the twisting operation occurring when the follower is on the dwell surface 237 which in this instance is identical with the dwell surface 235 and thus the needles are raised to the same height for this twisting operation. The declining surface 238 of the cam initiates the binding operation for coil No. 5 and the dwell surface 239 is the one occupied by the follower during the twisting operation of the binding wire on coil No. 5. This dwell is spaced from the center of cam 50 the same distance as is dwell 233 for coil No. 2. The sixth and final winding on form 62 has its tying cycle initiated by the follower riding the declining surface 240 of cam 50. When the follower reaches the dwell 241 on the cam the needles are raised to the same height for their twisting operation as in the case of the coil or winding No. 1 which involves the cam follower on the dwell 229. From the foregoing it may be seen that cam 50 actuates the needle housing 144 upwardly and downwardly on its supporting slide rods 142 and 143 in order to move the needles 157 to approach the respective six coils on the frame 62 at successive intervals and at proper height during one revolution of this cam 50.

NEEDLE REVOLVING MECHANISM

Besides reciprocating the needles longitudinally toward and away from the windings on the frames 62 and 63 to bind them, it is necessary also to revolve the needles in order to effect the twisting of the binding medium or wire. Revolving of the needles is effected by the mechanism illustrated by Figs. 3, 7, 9, 11 and 15.

The cam 43 is the controlling actuator for the needle-revolving mechanism, this cam being secured to and driven by the shaft 41 to which gear 40 is attached, said gear engaging and being driven by gear 39 as shown in Fig. 10. Cam 43 is constantly engaged by the cam follower 255 rotatably secured to one end of lever 256, the opposite end of said lever being pivotally secured to the hanger 257 attached to platform 24. A spring 258 has one end secured to lever 256 the other end to the standard 42 of the machine frame, this spring yieldably urging lever 256 so that its cam follower 255 is held in constant engagement with the outer peripheral surface of 75

cam 43. Near the end at which the cam follower 255 is mounted, lever 256 has an adjustable link 259 secured thereto, the other end of this link being secured to rack 260 of a rack and pinion drive. Fig. 9 illustrates this rack and pinion mechanism in cross section. A bracket 261 is attached to the platform 24, said bracket having a hub portion 262 provided with bearings in which the pinion 263, operatively meshing with the rack 260, is rotatably supported. The axial opening through the pinion 263 is provided with splines forming a slidable driving connection with corresponding splines 264 on the end of the drive shaft 149. This spline connection between the driving shaft 149 and the pinion 263 permits the reciprocating movement of said drive shaft 149 with the needle supporting housing 144 while still providing a rotatable driving connection between said pinion 263 and the splined portion 264 of the drive shaft 149. Therefore as the cam 43 in its rotation effects movement of lever 256 clockwise and counterclockwise about its pivotal support on the hanger 257, the rack 260 is reciprocated respectively to the left and to the right as regards Figs. 3 and 11, this reciprocation resulting in a rotation in opposite directions respectively of the drive shaft 149 which, as has been stated heretofore, is operatively connected with the needle supporting shaft 154 through the gears 150, 151 and 153.

The clockwise rotating cam 43 shown detailedly in Fig. 15 has its cam follower 255 riding at the start of the dwell surface 356 of the cam at the start of the machine cycle operation. When the follower reaches the descending camming surface 357 the spring 258, connected to lever 256, will effect operation of the rack 260 to rotate the pinion 263 so that the shaft 149 is likewise rotated. This rotation of shaft 149 results in a revolving of the needles 157, 30° backwardly so that said needles, in descending, are moved out of direct alignment with the binding wire to avoid contact therewith. The needles descend past said wire to bring their hooked ends beneath the level of said binding wire as indicated diagrammatically in Fig. 26. The follower 255 then rides over the dwell surface 358 of the cam and finally reaches the rising surface 359 which causes the needles again to be revolved 35° forwardly, however, in order that their hooked ends will be brought directly beneath and in alignment with the binding wire as diagrammatically indicated in Figs. 27 and 28. At this time the needle-raising mechanism becomes effective to draw the needle and its grasped binding wire upwardly to assume the position as shown in Fig. 32. During this time the cam follower 255 rides upon the dwell surface 360 of cam 43. Now the follower 255 is engaged by the sharply rising surface 361 of cam 43 resulting in a revolving forwardly of the needles 355° during which the needles twist the wire as indicated diagrammatically in Fig. 34. While the cam follower 255 rides upon the dwell surface 362 of cam 43 the needles are being reciprocated upwardly to their normal start position during which time they shed the binding wire twisted around the coil. After this follower 255 follows the descending cam surface 363 resulting in a revolving of the needles 360° backwardly into their initial start position where the cam follower will approach and ride upon the dwell surface 356. This sequence of operations revolving the needles by the cam 43 is repeated for every single revolution of the cam.

It will be understood that after the comple-

tion of the several operations revolving needles 157 by the cam 43, the indexing cam 55 becomes effective to shift the next successive winding on the spool into operative alignment with the needles.

Fig. 35 is a chart showing the various operations as they take place relatively to a certain point or time during the cycling of the machine. It indicates that the spool indexing cam 55 brings the respective windings on the spools successively into the binding position relatively to the needles at properly timed recurrent sequences and when all twelve windings on both spools 62 and 63 are completed again returns the spool-carrying clamping mechanism to its original start position.

It also shows that the needle reciprocating cam 50 rotates twice for each single revolution for the spool indexing cam 55 during each single revolution of cam 50, reciprocating the needles to manipulate a severed piece of binding wire for each one of the six windings on the first spool 62 and its second revolution repeats the operations to bind the six windings on the second spool 63.

It shows the wire cut off mechanism operating at the proper time to render a severed piece of binding wire available for the needles at the proper time and for each coil supported on the two frames 62 and 63.

It also shows the needle reciprocating cam 42 as rotating twelve complete revolutions for each two revolutions of the cam 50, or each single revolution of cam 55; that during each revolution of cam 43 the needles are turned backwardly, then forwardly twice in succession and finally backwardly again to their initial start position.

And finally this chart indicates the wire feeding clutch as operating in properly timed sequence with the wire cut off eccentric on the gear 40.

Fig. 36 indicates a simple wiring diagram including electrical controls for the machine. The power lines are indicated by the numerals 300 and 301 connected to the driving motor 26. A switch 302, which is the main, manually operated switch, is temporarily closed by the operator to start the machine. It is connected in the power line 300 having stationary contacts 303 and 304 which are bridged by the movable contact 305 when the operator actuates the switch to start the machine. Contact 304 of this switch is connected with a stationary contact 307 of switch 80 which has a second stationary contact 308, contacts 307 and 308 being engageable by the movable contact 309 under normal conditions. This switch 80 has an actuating stem 310 which is normally yieldably urged by spring 311 so that its associated bridging contact 309 engages the stationary contacts 307 and 308 of the switch. Switch 80, as has been described, is controlled by the spring loaded lever 85 under the influence of the form clamping mechanism. Lever 85 forms a part of a pivoted block 83 which also provides a track 84. This track 84, with its block 83 and lever 85, is normally held under the effect of spring 86 so that arm 85 engages the actuator 310 of the switch 80 to maintain the bridged contact 309 out of engagement with stationary contacts 307 and 308. However, when the clamping mechanism is manually actuated to move the clamping jaw 67 into clamping engagement with the frame 63 placed on the arbor 61, the associated lever 74 of said clamping mechanism is moved to engage the track 84 and

its block 83 to actuate said block clockwise as regards Fig. 36 thereby moving the arm 85, against the effect of its spring 86, away from the actuating member 310 of switch 80 so that the bridging contact 309 of said switch may, under the effect of its spring 311, engage stationary contacts 307 and 308 closing the circuit across this switch 80. As aforescribed, roll 87 on lever 74 will ride upon and along the track 84 during the entire time the winding bearing frames 62 and 63 move along the arbor 61 during cycling of the machine. However, if as stated before, relaxation or loosening of the clamping mechanism permits loosening of the collapsible frames 62 and 63 in any manner thereby presenting a possible misalignment or disintegration of the coils held in the frames 62 and 63, such loosening of the clamping mechanism would permit the spring 86 to become effective to actuate lever 85, block 83 and its track 84 so that lever 85 would again engage the actuating portion of the switch 80 to move contact 309 out of circuit engagement with its stationary contacts 307 and 308 thereby breaking the circuit to the motor 206 and causing it to stop.

The switch for stopping the motor and thus the machine when its cycle of operation on the coil supported by frames 62 and 63 have been completed, is designated by the numeral 191. This switch is normally open, its bridging contact 320 being held out of engagement with its associated contacts 321 and 322 by spring 323. Contact 322 of this switch is in electrical connection with contact 304 of the manual starting switch 302 and contact 321 of the switch 191 is connected with the power line 300. The switch 191 is, as has been described, controlled by the cam block 187 mounted upon the indexing cam 55. Upon completion of the cycling of the machine operations, this cam block 187 engages lever 188 to actuate its associated lever 189 against the effect of the spring 190 to move away from the actuator portion of the movable contact 320 thereby permitting the spring 323 of the switch 191 to move said bridging contact 320 out of engagement with its cooperating stationary contacts 321 and 322 to break the circuit between the line 300 and the contact 307 of switch 80. Under these circumstances the circuit to the driving motor 26 is broken and before winding support frames 62 and 63 are placed on the machine, the circuit on the motor is broken by both switches 80 and 191. When the coil supporting frames 62 and 63 are clamped into position on the arbor 61, switch 80 is automatically closed. However, the circuit to the motor 26 is still broken by the switch 191. To start the machine the operator actuates switch 302 so that its contact 305 connects stationary contacts 303 and 304 whereby a shunt circuit around the now open switch 191 is completed thereby connecting switch 80 and motor 26 with the power line 300 and rendering the motor operative. As soon as the motor 26 operates, cam 55 will be rotated and thus its camming block 187 is moved out of contact with lever 188 permitting spring 190 to actuate the lever 189 into engagement with the actuator of switch 191 resulting in a shifting of the contact 320 into circuit-making engagement with the stationary contacts 321 and 322 of switch 191 inasmuch as spring 190 overcomes spring 323. Now the circuit to the electric motor 26 is closed through both switches 191 and 80 and the manually operable switch 302 may be released. The machine will continue to operate to perform its repeated functions for binding the twelve windings on frames

62 and 63 until either by some unforeseen reason the safety switch 80 becomes effective upon failure of the clamping mechanism holding the winding supporting frames 64 and 63 properly clamped or by the switch 191 when the cycles of the machine to bind the twelve coils are completed.

The present machine automatically binds the convolutions of a plurality of coils wound upon collapsible forms thereby eliminating the expensive and time-consuming operation of tying each winding by hand.

The machine ties each coil with a binding wire and in such a manner that it is easily removable after the coils are placed in their respective positions on the part of the electrical machine into which they are nested. Removal of the binding wire is particularly necessary where the coils are placed in parts of an electric machine forming a sealed-in unit for a refrigerating system, for if these binding wires were left upon the coils after the electrical unit was assembled within the sealed compartment in which it was used, said wire may accidentally become loosened and plug up the circulatory system through which the refrigerant of the refrigerating machine is circulating and thereby cause damage and stoppage of the machine necessitating expensive repairs.

The machine is capable of operating throughout its complete cycle to tie twelve windings supported on two collapsible forms, means being provided in the machine which automatically stops machine operation and if and when the collapsible forms are released which would permit the coils thereon to become loose and disarranged and thereby present the possibility of damaging entanglements therewith by the needles as they move in juxtaposition with the coils when approaching the binding wire to grasp it.

The machine is also provided with means automatically effective to bring it to a stop after its entire cycle of operation to bind the twelve windings on the two forms has been finished.

The design and construction of the machine presents an efficient and rigid structure which is capable of continued usage without requiring extensive attention or adjustments there being no delicately constructed parts which are easily disarranged or rendered inoperative.

While the embodiment of the present invention as herein disclosed, constitutes a preferred form, it is to be understood that other forms might be adopted.

What is claimed is as follows:

1. A machine for binding the wire convolutions of a plurality of separate coils, the convolutions of all of the coils comprising a single, continuous wire, comprising in combination, means supporting the separate coils in spaced, side by side relation; means operative successively to shift said coil supporting means for moving each coil into a predetermined binding position on the machine; means operative to move binding wire into proper position relatively to the coil in binding position; means operative to sever a predetermined length of said binding wire adjacent the coil to be bound; reciprocative and revolvable means operative to grasp said severed length of binding wire, pull it over the adjacent coil, twist it about said coil to bind it and then shed said twisted binding wire as said reciprocating means returns to initial position.

2. A machine for binding the wire convolu-

tions of each of a plurality of coils wound from a single, continuous length of wire, side by side on collapsible spools, said machine comprising in combination, a stationary arbor, shiftably supporting the coil carrying spools; indexing means operative to shift the spools on the arbor for moving the coils successively into the binding position on the machine; wire feeding means periodically operative to feed binding wire into a predetermined position relatively to the coil in the binding position; sheering means operative to sever a predetermined length of the binding wire adjacent the coil in binding position; two, spaced hook-end needles longitudinally reciprocative to engage and grasp the severed length of binding wire and pull it against and around the sides of the coil in binding position, said needles being revolvable about an axis parallel to and midway between them for twisting the binding wire about the respective coil, reciprocation of the needles to normal position separating them from the binding wire twisted about the coil.

3. A machine for binding the wire convolutions of each of a plurality of coils wound from a single, continuous length of wire, side by side on collapsible spools, said machine comprising in combination, a stationary arbor shiftably supporting the coil carrying spools; indexing means operative to shift the spools on the arbor for moving the coils successively into the binding position on the machine; wire feeding means periodically operative to feed binding wire into a predetermined position relatively to the coil in the binding position; shearing means operative to sever a predetermined length of the binding wire adjacent the coil in binding position; two parallel, hook-end needles reciprocative longitudinally and revolvable about an axis parallel to and midway between the needles; power driven means operative, first to reciprocate the needles toward the coil in binding position so that the hook-ends of the needles are beneath the binding wire, second, to revolve the needles so that their hook ends are engageable with the binding wire, third, to reciprocate said needles so that their hook-ends grasp the binding wire and draw it against the coil and along both sides thereof until the hook-ends of the needles are above the coil, fourth, to revolve the needles for twisting the binding wire about the coil to bind the several convolutions thereof, fifth, to reciprocate the needles for returning them to normal position, thereby separating the twisted binding wire from the needles, and sixth, after being returned revolving the needles to their normal start positions, all in properly timed sequence and recurrent for each coil.

4. A machine for binding the wire convolutions of each of a plurality of coils wound from a single, continuous length of wire, side by side on collapsible spools, said machine comprising in combination, a stationary arbor shiftably supporting the coil carrying spools; indexing means operative to shift the spools on the arbor for moving the coils successively into the binding position on the machine; wire feeding means periodically operative to feed binding wire from a supply through aligned openings in two stationary, spaced supporting blocks, which support the binding wire extending transversely beneath the convolutions at the one side of the coil; shearing means operative to sever a predetermined length of the block supported wire from the main feed supply; two spaced, parallel needles secured at one end, the

other ends each having a wire receiving notch, the notch in one needle having its opening directly opposite the notch in the other needle, said needles being reciprocative longitudinally and revolvable about an axis parallel to and midway between said needles; and power driven means connected with the needles and operative, first to reciprocate the needles toward the coil, one needle on each side of the coil so that the notched ends of the needles are beneath the coil convolutions and above the binding wire, second to revolve the needles in one direction to disalign the needles from the binding wire; third, reciprocate the needles to position the notched ends thereof below the binding wire, fourth, to revolve said needles in the opposite direction to place their notches beneath the binding wire, fifth to reciprocate the needles for causing the notches thereof to receive and grasp the binding wire and pull it from the supporting blocks against the coil convolutions and along both sides thereof until the notched ends of the needles are above and clear the coil convolutions, sixth, revolving the needles in said opposite direction for twisting the grasped binding wire around the coil convolutions, seventh, to reciprocate the needles to shed the twisted wire and move into normal position, eighth, to revolve the needles in said one direction to return them to normal start position, all in properly timed sequenc and recurrent for the respective coils on the spools.

5. In a machine for binding the several convolutions of each of a plurality of separately formed coils wound from a single, continuous length of wire, side by side on a collapsible form, the combination with a stationary arbor upon which the coil carrying form is slidably supported; of slide-bars parallel to the arbor and shiftably supporting a block provided with a rigid clamp jaw engageable by the form when it is placed on the arbor; a second block shiftably supported by the slide-bars, said second block hingedly supporting a clamp jaw operable into one position to permit placing of the form upon or removal of it from the arbor and in another position to engage the form and hold it clamped against the rigid clamp jaw; mechanism supported between the two blocks and operatively connected to the hinged clamp jaw, said mechanism being manually operative to move and lock the hinged clamp jaw in form clamping position; a control device engaged and actuated by said mechanism when operated into its form clamping position, for maintaining the machine in operation while the hinged jaw is in form clamping position; and means operative to bind the convolutions of each coil.

6. In a power driven machine for binding the several convolutions of each of a plurality of separately formed coils wound from a single, continuous length of wire, side by side on a collapsible form, the combination with a stationary arbor for receiving and slidably supporting the form carrying the coils; of slide-bars attached to the machine, parallel to the arbor; two blocks slideable on the slide-bars and held in spaced relation, one block having an erect, rigid clamp jaw extending toward the arbor and engageable by the form on the arbor, the other block hingedly supporting a similar, cooperating clamp jaw which is movable into its prostrate or loading position and into its erect or form clamping position parallel to the rigid clamp jaw; a crank provided with a toggle lever connected to the hinged clamp jaw, said crank being operative to actuate the hinged clamp

jaw and lock it in its form clamping position; a control device normally rendering the power drive for the machine inoperative; means connected to the crank and actuated thereby, while said crank locks the hinged clamp in its form clamping position, to engage, actuate and hold the control device in power drive activating position; and mechanism operative to bind the convolutions of each coil.

7. In an electric motor driven machine for binding together the convolutions of each of a plurality of coils wound from and connected together by a single, continuous length of wire, side by side on a collapsible form, the combination with an elongated, stationary arbor for slidably supporting said form; a clamp consisting of two jaws between which the collapsible form on the arbor is clamped, both jaws being movable on slide-bars longitudinally of the arbor, one jaw being rigid, the other swingable into prostrate, loading or erect, clamping positions; tying means movable relatively to the form on the arbor for binding the several coils on said arbor one at a time; means connected to the clamp and periodically operative to shift said clamp for sliding the form on the arbor successively to align each coil with the tying means; manually operable means including a crank and a toggle lever supported on the rigid clamp and connected to the swingable clamp for operating it, said toggle lever locking the swingable clamp in its erect, clamping position; an electric switch normally, yieldably closed in circuit with the electric motor; a lever yieldably urged to engage and open said switch to render the motor inactive, said lever having a track portion parallel to the clamp supporting slidebars; and means connected to the crank and movable thereby to engage the track and actuate the lever to disengage and effect closing of the switch which remains closed while said crank and its toggle lever hold the swingable clamp in its form clamping position during the entire movement of the form on the arbor.
8. In an electric motor driven machine for binding together the convolutions of each of a plurality of coils wound from and connected together by a single, continuous length of wire, side by side on a collapsible form, the combination with an elongated, stationary arbor for slidably supporting said form; a clamping mechanism consisting of two spaced jaws between which the form on the arbor is clamped, one jaw being rigidly erect, the other being tiltable to permit placing and removal of the form upon and from the arbor, both jaws being secured to the machine so as to be movable longitudinally of the arbor; binding mechanism on the machine operative to bind the convolutions of each coil on the form as the respective coils are moved into operating alignment with said mechanism by the clamping jaws; manually operable means having a crank actuated toggle lever connected to the tiltable clamp for operating it, said toggle lever locking the tiltable clamp in form clamping position; shifting levers connected to the clamping mechanism; a cam operatively connected to one of said shifting levers, said cam, during one revolution, being operative periodically to actuate the clamping mechanism in one direction for successively aligning the respective coils with the binding mechanism; and means yieldably urging the form in the other direction and for returning the form to its initial position on the arbor; two electric switches in circuit with the electric motor, one switch being opened and closed by the said cam,

the other switch being opened by actuation of the tiltable clamp to its form releasing position.

9. A machine in accordance with claim 8, in which, however, the two switches in circuit with the electric motor, are also connected in series with each other, the one switch being held normally open by the cam which effects shifting of the clamping means and closes when said cam is rotated to start its cycle of clamp shifting operations, the second switch being a safety switch normally open, but is closed by the mechanism which actuates the tiltable clamp and remains closed as long as the clamp securely holds the form, and a third switch, connected in parallel with the cam operated switch and in series with the second switch, said third switch being normally open but temporarily, manually closable to circumvent the cam operated switch for starting the machine.

10. In a machine for binding the several convolutions of each of a plurality of coils wound from a single, continuous strand of wire side by side on a collapsible form, the combination with a stationary arbor upon which said form is slidably supported; binding means operative to fold and twist a piece of binding wire about the convolutions of each coil; a shiftable clamping mechanism operative to hold the coil carrying form together and to shift said form progressively along the arbor for aligning each coil with the binding means; a binding wire supply spool and wire straightening means through which said binding wire passes as it is drawn from the spool; cooperating feed rollers between which the binding wire passes, said feed rollers being operative, intermittently to advance said binding wire through a guide to two supporting blocks aligned with the binding means, one of said rollers being provided with a one-way clutch by means of which the roller is actuated in one direction only; a brake on said one roller operative to resist rotation of the roller in the other direction; and means connected to the clutch, operative periodically to turn said clutch for actuating it through a predetermined range of movement in the said one, roller turning direction.

11. A machine as defined by claim 10, in which the binding means is periodically moved from a position remote from the coil to be housed into a position adjacent the coil for binding it, and the clutch actuating mechanism is active to rotate the binding wire feed rollers for advancing the feed wire to the two supporting blocks when the binding means is in the position most remote from the coil to be found, the clutch brake having an unbalanced, spring loaded lever which provides a lesser resistance to rotation of the clutch actuated feed roll in the wire advancing direction than in the other direction.

12. A machine as defined by claim 10, in which a shear block is provided in the machine, spaced predeterminately from one of the supporting blocks through which the binding wire is introduced by the feed rolls; a rotatable knife engaging the shear block and cooperating therewith to sever the binding wire; and power driven means operatively connected to the knife for actuating it to sever the binding wire as the tying means starts its coil approaching movement and before said means has reached the binding wire.

13. In a machine for binding the respective convolutions of a plurality of coils wound upon a collapsible form, the combination with a stationary arbor for slidably supporting said form; of a clamping means engaging and holding the

collapsible form together, said clamping being movably carried by the machine and operative intermittently to move the form along the arbor so that each coil thereof is moved into the binding position on the machine and held there for a predetermined period of a machine cycle; a binding wire supply; means intermittently operative for moving the binding wire transversely through the loop of the coil held in the binding position; means periodically operative to sever the binding wire; and binding means for grasping, pulling and twisting the severed piece of binding wire up to and about the convolution of the coil in the binding position, said binding means consisting of a pair of spaced, parallel needles, each secured to a rotatable member at one end; the other ends of the needles being notched similarly to a crochet needle, said rotatable member being operative to revolve said needles about the axis of said member and being carried by a housing movable on supporting standards provided on the machine for rendering the needles reciprocative longitudinally.

14. A machine in accordance with claim 13, in which the binding means consists of a housing movably supported by standards provided on the machine, said housing having two rotatable shafts journaled therein and extending therefrom; motion transmitting mechanism in said housing, connecting said shafts; a pair of spaced, parallel needles secured to one of said shafts and revolvable thereby about the axis of the shaft, each needle having a crochet needle type notch at its free end; a link connected to the housing for reciprocating the housing on the standards whereby the needles are reciprocated toward and away from the coil in the binding position on the machine; and cam operated mechanism connected to the link and to the other of said shafts, said mechanisms being operative to reciprocate the link to raise and lower the housing, and to rotate said other shaft back and forth for revolving the needles, all at proper intervals and in recurrent sequence.

15. In a machine for binding the convolution of a coil wound upon a collapsible form, the combination with means for supporting the coil bearing form in the binding position on the machine; of a binding wire introduced through the coil transversely thereof; means operative to grasp, pull and twist the binding wire about the coil convolutions to bind them against separation when the coil is removed from the form, said means consisting of a housing; means reciprocatively supporting the housing above the coil to be bound; a driven shaft and a driving shaft with connecting motion transmitting means therebetween carried by the housing; two spaced and parallel needles secured to the driven shaft and extending toward the coil to be bound, the outer end of each needle having a crochet-needle type hook, one opposed to the other; a link secured to the housing; a cam operated lever connected to the link for reciprocating it at proper intervals, in the proper direction and for predetermined distances; a splined portion on the driving shaft; a rack and pinion operatively connected to the splined portion of the driving shaft so as to permit said driving shaft to move axially relatively to the said rack and pinion but to be rotatably oscillated thereby; a link connected to the rack; and a cam operated lever connected to the link for reciprocating the rack which effects revolving of the needles about the axis

of their supporting shaft in one direction or the other through lengths of movement and at intervals predetermined by the cam.

16. In a machine for binding the convolutions of each of a plurality of coils varying in size and wound upon a collapsible form, the combination with an arbor upon which said collapsible form is slidably supported, of a clamp movable longitudinally of the arbor and operative to hold the collapsible form together and to move it along the arbor in intermittent steps for bringing the successive coils on the arbor into the binding position on the machine; a cam actuated lever connected to the clamp for moving the clamp intermittently in one direction to move the coils successively into the binding position; a pneumatic actuator connected to said lever, said actuator being operative to hold the lever in operative engagement with the cam and to move the coil supporting clamp back to its normal position under the control of the cam; and means operative to secure a binding wire about the convolutions of each coil when said coils are moved into the binding position on the machine.

17. In a machine for binding the convolutions of each of a plurality of loop-shaped coils of different sizes wound upon a collapsible form, the combination with an arbor for slidably supporting the form; shiftable form clamping means operative to move the form along the arbor for bringing the respective coils into the binding position on the machine; a binding wire feeding mechanism operative to introduce binding wire transversely through the loop of the coil in the binding position; a housing in which a driving and a driven shaft and a connecting gear are journaled, said housing being reciprocatively mounted on the machine rendering said housing movable toward and away from the coil in the binding position; two spaced and parallel needles attached at one end to the driven shaft and extending longitudinally therefrom, the outer, free end portions of said needles having crochet-needle type hook formations, one opposed to the other; a splined portion on the driving shaft; a pinion of a rack and pinion mechanism operatively engaging the splined portion of the driving shaft for effecting a rotative driving connection between the pinion and shaft while permitting the shaft to reciprocate longitudinally in said pinion; a link connected to the housing; pivoted levers connected respectively to the link and to the rack; power driven cams for operating said levers, one cam to reciprocate the housing and the other to revolve the needles about the axis of their supporting shaft, said cams having provisions which, while a coil is in the binding position, first lowers the housing to move the needles toward the coil so that each needle passes alongside the top loop of the coil during which time the other cam revolves the needles through a predetermined distance backwards as regards their open hook portions, before the needles reach the binding wire in their descent, then, after the hook ends of the needles have passed the binding wire in their descent, again revolve the needles forward the same distance to position their hook ends immediately beneath the binding wire, the one cam then reversing the direction of housing reciprocation so that as the needles are raised the hook end thereof will grasp the binding wire and draw it upwardly against the inner surface of the coil loop and alongside the loop, said one cam having a dwell which effects discontinuation of the upward reciprocation of

the housing when the wire grasping, hook ends of the needles are above the loop of the coil, at which time the other cam becomes active to revolve the needles substantially 350° to twist the wire around itself for binding the coil convolutions in the upper half of the coil loop, following which said one cam again becomes active to reciprocate the housing upwardly and into its initial, normal position for shedding the twisted binding wire, the said other cam then revolving the needles backward to their normal, initial position, said cam operations being repeated for each coil on the frame and after the respective coils have been moved into the binding position on the machine.

18. A machine in accordance with claim 17 in which the said one cam has provisions to reciprocate the housing upwardly to different levels for the twisting operation by the other cam, to compensate for the differences in the loop sizes of the several coils to be bound.

19. In a machine for binding a plurality of loop coils wound on a collapsible form, the combination of a form carrier; a clamp manually to engage and hold the form together on the carrier and power operated intermittently to move the form on the carrier for bringing each coil on the form into a fixed position for binding purposes, and for returning the form to the initial position on the carrier when all of the coils have been bound; cam means for actuating the clamp along the carrier; means for introducing and holding binding wire transversely of the coil in the binding position, said wire extending through the loop of the coil; binder means movable to grasp the wire, pull it about the convolutions at each side of the loop coil, twist it about said convolutions to bind them and then release the binding wire; power driven cams operatively connected to the binder means for actuating it in properly timed and recurrent sequence for binding all of the coils on the collapsible form; means rendered effective by the clamp actuating cam for stopping the machine after all of the coils have been bound and the clamp has been returned to its initial position; and means rendered effective to maintain machine operative while the form is securely held by the clamp, said means being rendered effective to stop machine operation at any time the clamp releases the coil carrying form.

20. In a machine for binding the convolutions of each of a plurality of coils wound and supported upon a collapsible form, the combination with an arbor upon which said form is supported and moved; a clamp engaging the form to hold it together, said clamp being movable intermittently in one direction to shift each coil on the form into coil binding position and to return the form to the initial position after all coils have been bound; a binding wire supply and means for feeding the wire transversely through the coil when it is in binding position; shearing means operative to sever a predetermined length of wire extending through the coil; spaced, parallel hooked needles reciprocative to approach, grasp and draw the several length of binding wire about the coil loop and revolvable to twist said wire about the one side of the coil loop; and power driven means for actuating the machine, said power driven means consisting of a driving motor operatively connected to a pinion, two gears mounted upon a common shaft, one gear operatively engaging the pinion and driven at a predetermined speed thereby, the second gear operatively engaging a third gear of the same

31

size, the first gear eccentrically supporting a link operatively connected to the binding wire feeding means for operating it once for each revolution of the gear; a lever eccentrically connected to the said third gear, operatively connected to the binding wire shearing means for actuating it once for each revolution of said third gear; a shaft supporting said third gear, a pinion and the cam operatively connected to the needles for revolving them; a fifth gear connected to the last mentioned pinion said fifth gear rotating once to each six revolutions of its driving pinion; a shaft supporting a pinion and a cam having provisions connected with the needles for reciprocating them; said last mentioned pinion being operatively connected to a sixth gear

5

coaxially carrying a cam operatively connected to the form engaging clamp for shifting it in one direction and controlling pneumatic means connected to the clamp and operative to return the clamp into its initial position after all coils have been tied.
